UNITED STATES PATENT OFFICE.

ERASTUS WILLIAMS APPELMAN, OF CLERMONT, IOWA, ASSIGNOR TO ANNA LARRABEE, OF CLERMONT, IOWA.

DESIGN FOR A GAME BOARD.

Application filed October 12, 1923. Serial No. 7,479. Term of patent 14 years.

To all whom it may concern:

Be it known that I, ERASTUS WILLIAMS APPELMAN, a citizen of the United States, residing at Clermont, in the county of Fayette and State of Iowa, have invented a new, original, and ornamental Design for a Game Board, of which the following is a specification, reference being had to the accompanying drawing, forming part thereof.

The figure is a plan view of a game board showing my new design.

I claim:—

The ornamental design for a game board, as shown.

ERASTUS WILLIAMS APPELMAN.
